CLAIM

I claim the ornamental design for a box for smoking items, as shown and described.

DESCRIPTION

FIG. 1 is a top perspective view in a closed state of a box for smoking items showing my new design;

FIG. 2 is a top plan view of the box for smoking items in the closed state of FIG. 1;

FIG. 3 is a bottom plan view of the box for smoking items in the closed state of FIG. 1;

FIG. 4 is a right side elevation view of the box for smoking items in the closed state of FIG. 1;

FIG. 5 is a left side elevation view of the box for smoking items in the closed state of FIG. 1;

FIG. 6 is a front elevation view of the box for smoking items in the closed state of FIG. 1;

FIG. 7 is a back elevation view of the box for smoking items in the closed state of FIG. 1;

FIG. 8 is a top perspective view in an open state of the box for smoking items of FIG. 1;

FIG. 9 is a top plan view of the box for smoking items in the open state of FIG. 1;

FIG. 10 is a bottom plan view of the box for smoking items in the open state of FIG. 1;

FIG. 11 is a right side elevation view of the box for smoking items in the open state of FIG. 1;

FIG. 12 is a left side elevation view of the box for smoking items in the open state of FIG. 1;

FIG. 13 is a front elevation view of the box for smoking items in the open state of FIG. 1;

FIG. 14 is a back elevation view of the box for smoking items in the open state of FIG. 1; and,

FIG. 15 is an exploded perspective view of a box for smoking items of FIG. 1.
